UNITED STATES PATENT OFFICE.

GREGG K. MILLS, OF CHICAGO, ILLINOIS.

SOUND TRANSMITTER FOR PHONOGRAHS.

Application filed December 31, 1919. Serial No. 348,681.

To all whom it may concern:

Be it known that I, GREGG K. MILLS, citizen of the United States, residing at Chicago, in the county of Cook and State of Illinois, have invented a certain new and useful Improvement in Sound Transmitters for Phonographs, of which the following is a full, clear, concise, and exact description.

My invention relates to phonograph transmitters and has for its general object the elimination of vibrant connection between the body of the transmitter sound box that is supported upon the tone arm and a mounting that is in supporting relation to the diaphragm, and is preferably also the mounting for the stylus carrier, whereby not only vibrations imparted to the stylus bar or other stylus carrier, but vibrations imparted to the diaphragm also, are prevented from finding their way to the body of the transmitter box and the tone arm upon which the transmitter box body may be directly mounted.

In the preferred embodiment of my invention, I embrace the diaphragm, the stylus bar and a mounting for these elements in a unitary structure detachably applicable to the box body with sound insulation between this mounting and the box body for the purpose stated. I do not wish to be limited to this construction however, as I consider it to be within the scope of my invention to employ the insulated mounting in supporting relation to the diaphragm, particularly where this mounting also supports the stylus carrier, whether such mounting forms an element of a unitary structure with the diaphragm and stylus carrier or not.

I will explain my invention more fully by reference to the accompanying drawings illustrating preferred embodiments thereof and in which Fig. 1 is a front view, with parts broken away, of a transmitter made in accordance with the preferred embodiment of the invention; Fig. 2 is a sectional view on line 2—2 of Fig. 1; Fig. 3 is a perspective view of the preferred mounting for the diaphragm; Fig. 4 is an enlarged sectional view of a part of the structure as it is illustrated in Fig. 2; Fig. 5 is a front view, with parts broken away, of another form of the invention; Fig. 6 is a sectional view on line 6—6 of Fig. 5; Fig. 7 is a perspective view of the mounting of Figs. 5 and 6 that is in supporting relation to the diaphragm and which supports the stylus carrier; and Fig. 8 is an

enlarged sectional view of a part of the modified structure as it appears in Fig. 5.

Like parts are indicated by similar characters of reference throughout the different figures.

Referring first more particularly to the structure illustrated in Figs. 1 to 4 inclusive, I have there illustrated a metallic tone arm portion 1 upon which is mounted the metallic body 2 of the sound box of a transmitter. This box body has an annular channel 3 in its front face. An annular body or cushion 4 of sound insulating material, such as rubber, is received in the channel 3 to be flush with the front face of the box body. This annular body of sound insulating material itself has an annular channel 5 in which is received the flanged base 6 of a metallic mounting ring 7, said base projecting beyond and within said ring to form outer and inner annular ledges. In the structure shown in Figs. 1 to 4 inclusive the metallic mounting ring is a component element of a unitary structure that includes the sound transmitting diaphragm 8 and the metallic stylus bar 8' in connection, at one end, with the central portion of the diaphragm. The diaphragm is supported by the ledge formed by the inner portion of the ring base 6, there being a sound insulating cushion 9 between the peripheral portion of the rear face of the diaphragm and this ledge. Another sound insulating cushion 10 is interposed between the peripheral portion of the front face of the diaphragm and a metallic clamping ring 11 which is secured to the front of the mounting ring 7 by means of screws 12. The sound insulating cushion gaskets 9 and 10 are preferably of tubular rubber, being sufficiently collapsed by the ring 11 to give the diaphragm a substantially fixed position with respect to the sound box body 2, without, however, making these gaskets so rigid as to be deprived of their cushioning and sound insulating function. The metallic mounting ring 7 has a bifurcated extension between whose branches 13, 14 is pivoted the stylus bar 8'. In accordance with common practice, the stylus bar is provided with lateral trunnion extensions 15 recessed in their ends to receive the inner ends of trunnion screws 16 secured in the bifurcation arms 13, 14. The diaphragm and stylus bar being usually assembled before these elements are assembled in a unitary structure with the metal mounting ring 7 and metal clamping

ring 11, said clamping ring is the last of these elements to be placed in position, on which account I form therein a radial slot 17 to permit the clamping ring to be passed over stylus bar. As is usual, the stylus bar is also constituted a stylus carrier, having a socketed portion 18 at its lower end for receiving a stylus 19 that is held within said socket by a clamping screw 20.

- 10 The unitary structure embracing the mounting ring 7 and parts carried thereby are, after the complete formation thereof, assembled with the sound box body 2 by placing the flanged base 6 of the mounting ring 7 within the annular channel 5 in the annular body of sound insulating material 4. The cushioning and sound insulating rubber gasket 21 is placed about the ring 7 and upon the outer portion of the ring base 6, and is clamped between this ring base and the clamping ring 22 by means of clamping screws 23 passing through the clamping ring into the sound box body 2. There is thus provided a mounting for the stylus bar or other stylus carrier which also constitutes a mounting for the diaphragm or is in supporting relation thereto, and sound insulation between this mounting and the sound box body to limit, as far as practicable, the direct transmission of sound vibrations from the record to the diaphragm.

In Figs. 5 to 8 inclusive there is illustrated another form of the invention, similar parts in both sets of figures being given respectively similar characters of reference. In the modified structure the annular gasket 4 and the channel 5 within this gasket surround the entire metallic ring 7, the gaskets 9 and 10, and the diaphragm 8, instead of being in a plane parallel with these elements, the latter being the case with the structure of Figs. 1 to 4 inclusive. The peripheries of the gaskets 9 and 10 engage the inner face of the surrounding ring 7 (Fig. 5) so that the ring is in supporting relation to these gaskets and the diaphragm 8 disposed between the gaskets. In the modified structure

the metallic clamping ring 11 has an outer flange 24 clamped upon the box body by clamping screws 25. This clamping ring 50 has an annular channel 26 constituting a continuation of the channel 3 in the box body for receiving the sound insulating cushion 4. The inner wall 27 of the channel 26 serves to clamp the gaskets 9 and 10 and the diaphragm 8 that is between these gaskets in assembly with the box body.

While I have herein shown and particularly described preferred embodiments of my invention I do not wish to be limited to the precise details of construction shown as changes may readily be made without departing from the spirit of my invention, but having thus described my invention I claim as new and desire to secure by Letters Patent the following:—

A sound transmitter comprising in combination, a sound box having a body portion for attachment to a tone arm, said body portion being disc-like in form and provided with an annular channel near its periphery, insulating material made in annular form and fitted into said channel, and in turn provided with an annular channel, a metallic ring fitted into said last mentioned channel, said ring being provided with outwardly projecting members serving as supports for a sound transmitting element, said projections extending through said insulating material and also through said body portion, a diaphragm mounted in said ring, a sound transmitting element connected with the diaphragm and pivotally supported by said projecting members, and a metallic clamping ring fitted outside of said insulating material so as to hold the same and said mounting ring in position, and screws holding said clamping ring attached to said body portion.

In witness whereof, I hereunto subscribe my name this 22nd day of November A. D., 1919.

GREGG K. MILLS.
